Primary Examiner — Jack Reickel*Assistant Examiner* — Rachel A Voorhies(74) *Attorney, Agent, or Firm* — Knobbe, Martens, Olson & Bear, LLP(57) **CLAIM**

The ornamental design for a vehicle steering yoke, as shown and described.

DESCRIPTION

FIG. 1 is a perspective view of a vehicle steering yoke.

FIG. 2 is a front view thereof.

FIG. 3 is a rear view thereof.

FIG. 4 is a right-side view thereof.

FIG. 5 is a top view thereof.

FIG. 6 is a left-side view thereof.

FIG. 7 is a bottom view thereof; and,

FIG. 8 is a front view thereof within a vehicle.

The broken lines illustrating the inside of a vehicle, in FIG. 8, depict environmental structure that form no part of the claimed design.

1 Claim, 8 Drawing Sheets(56)
